TOY MACHINE GUN

Francisco S. Alonso, Brooklyn, N. Y.

Application June 28, 1935, Serial No. 28,952

1 Claim. (Cl. 124—13)

My invention relates to improvements in toy machine guns, or cannons, for shooting shot, pellets, or similar missiles.

The primary object of my invention is to provide a simply constructed self-loading toy gun operative easily by a small child to rapidly eject such missiles for a considerable distance.

Another object of my invention is to equip such a gun with a gravity magazine feed, and an ejecting mechanism, and a single rotatable member for controlling said feed and operating said mechanism repeatedly during a single rotation of said member.

Other and subordinate objects will presently appear and the nature of my invention will be clearly understood when the following description and claim are read in conjunction with the accompanying drawing.

In said drawing:

20 Figure 1 is a view in top plan, with parts shown in section, of my improved gun showing the interior mechanism, the parts thereof being in normal position.

25 Figure 2 is a view in transverse section, taken on the line 2—2 of Figure 1, and looking in the direction indicated by the arrows.

Figure 3 is a view in longitudinal section, taken on the line 3—3 of Figure 1, and looking in the direction indicated by the arrows.

30 The illustrated embodiment of my invention comprises a casing 1 preferably rectangular in shape, and including a flat bottom plate 2, side and end walls 3 and 4, respectively, and a top plate 5 removably secured in position as by screws 35 6. A cylindrical barrel 7 projects from the casing 1 through one end wall 4 and is secured to the bottom plate 2 by flanges 8 on said barrel and screws 9 passing through said flanges. The inner breach end of the barrel 7 is curved in the arc of

40 a circle as at 10, and provided opposite the bottom plate 2 with a similarly curved slot 11 and a flat ledge 12 at one end of said slot, all for a purpose presently seen. An angle bracket 13 is secured in said casing 1 to the bottom plate 2 there-

45 of as by screws 14, an arm 15 of said bracket projecting over the ledge 12 in spaced relation thereto.

A magazine in the form of a tube 16 is suitably secured in said bracket arm 15 to open on to said ledge 12 and to extend through the cover plate 7 in a substantially vertical position. The magazine 16 is designed to contain shot or pellets 17 to be fed under the influence of gravity to the ledge 12.

Pivoted as at 18 to the bottom plate 2 are a pair of loading and ejecting arms 19 and 20, respectively, swinging intermediate the arm 15 and the ledge 12 in an arc concentric with that of said slot 11. A pair of springs 21 and 22, respectively, one for each of said loading and ejecting arms are suitably connected to the related arm, and to a bracket 24, fixed to the bottom plate 2, said springs holding the arms in normal position and under tension. The normal position of the loading arm 19 is established by a stop 25 on said bracket 24 and that of the ejecting arm 20 by the ledge 12 as best shown in Figure 2. The free end of loading arm 19 is provided with an aperture 27 which, in the normal position of said arm, is axially aligned with the magazine tube 16 so that a ball or pellet 17 is contained in said aperture 27 and rests on the ledge 12. An arcuate extension 28 formed on the loading arm 19 acts as a shutter, closing said magazine tube 16 when the loading arm 19 is moved from normal position. A pick-up connection is provided between the arms 19 and 20 in the form of a lug 29 on the arm 19 and over-lying one edge of the arm 20 so that the arm 20, when moved a short distance 25 from its normal position, will pick up the arm 19. The ejector arm 20 is provided with an ejecting lug 30 extending into the barrel 7 by way of the slot 11.

Rotatably mounted on a bracket 31 extending from the casing 1 is an operating member in the form of a two-armed lever 32 having a crank member 33 thereon and arranged so that its arms enter the casing 1 through a slot 34 therein and engage and release the lug 35 on the lever 20 with 30 a wiping action.

In operating my improved gun the casing 1 is positioned upon a floor, table, or the like and held by one hand thereagainst and the operating member 32 is rotated in the direction indicated by the arrow. Rotation of member 32 engages the arms thereof with the aforementioned lug 35 and moves the ejector arm 20 from normal position to the extreme position shown in dotted lines in Figure 1 at which point said member 32 wipes past the lug 35 and releases said lever. At an intermediate point in the movement shown by dotted lines in Figure 1, the lever 20 picks up loading lever 19 by way of the lug 29 and moves the shot 17 contained in the aperture 27 off the ledge 12 and over the slot 11, said shot falling into the barrel 7 by way of said slot and in front of the ejector lug 30. During such loading movement of the arm 19, the extension 28 closes the magazine 16. Upon 50 55

release of the ejector arm 20, it snaps back to normal position under the combined action of the springs 21 and 22, the shot is ejected and the loading arm 19 returned to normal position as will 5 be clear. It will be seen that the two-armed operating member 32 controls the ejector lever 20 and the loading lever 19 to effect repeated loading and firing of said gun during a single rotation of said member. In this connection, it is to be understood 10 that the member 32 may embody a greater number of arms if desired, a two-armed lever being shown merely for the purpose of illustrating the principles of the invention.

Other modifications may also be resorted to 15 without departing from the inventive concept or the scope of the appended claim.

What I claim is:

A toy machine-gun for shooting shot comprising, 20 a flat casing adapted for location in horizontal position, a barrel having an arcuately curved breech end mounted in said casing and provided at said end with an arcuate slot in the top thereof

terminating at its forward end in a shoulder portion, said barrel having an elevated ledge in front of said shoulder portion, a gravity feed magazine adapted for depositing shot on said ledge, a horizontally swingable ejector arm having a free end 5 guided for movement on the edges of said slot and an ejector lug extending into the breech end of the barrel, said arm being tensioned against movement toward said breech end and normally bearing against said shoulder portion, a loading arm 10 horizontally swingable to convey shot deposited on said ledge to said slot for gravitational movement into said breech end, said loading arm being tensioned against such movement and having a free end normally positioned over said ledge, a 15 manipulative member for moving the ejector arm toward the breech end of the barrel with a wiping action, and a lug on the loading arm located in the path of movement of the ejector arm providing a pick-up connection between said arms. 20

FRANCISCO S. ALONSO.
